UNITED STATES PATENT OFFICE

150,466

DESIGN FOR A PRICE TAG MOLDING AND TRIM

Fred G. Schuler, Youngstown, Ohio, assignor to
Youngstown Manufacturing Inc., Youngstown,
Ohio, a corporation of Ohio

Application May 16, 1946, Serial No. 130,027

Term of patent 3½ years

(Cl. D13—16)

To all whom it may concern:

Be it known that I, Fred G. Schuler, a citizen of the United States, residing at Youngstown, in the county of Mahoning and State of Ohio, have invented a new, original, and ornamental Design for a Price Tag Molding and Trim, of which the following is a specification, reference being had to the accompanying drawing, forming part thereof.

Figure 1 is a perspective elevation of a price tag molding and trim, showing my new design.

Figure 2 is a perspective elevation of an inverted section of a price tag molding and trim, showing my new design.

Figure 3 is a perspective elevation of the back portion of a section of a price tag molding and trim, showing my new design.

I claim:

The ornamental design for a price tag molding and trim, as shown.

FRED G. SCHULER.
